UNITED STATES PATENT OFFICE.

SYDNEY BURT GARDNER, OF BENSON, MINNESOTA.

PIPE-SMOKER'S KIT.

Application filed March 2, 1921. Serial No. 443,964.

To all whom it may concern:

Be it known that I, SYDNEY BURT GARDNER, a citizen of the United States, residing at Benson, in the county of Swift and State 5 of Minnesota, have invented certain new and useful Improvements in Pipe-Smokers' Kits; and I do hereby declare the following to be a full, clear, and exact description of the invention, such as will enable others 10 skilled in the art to which it appertains to make and use the same.

The present invention relates to improvements in smokers' kits, and has for an object to provide a compact case adapted to hold 15 a pipe, tobacco, and matches so that these various articles may be carried about on the person of the smoker and be at all times on hand when their use is required.

Another object of the invention is to provide 20 a compact, simple and economical case or kit for the use of pipe smokers in which is also provided a humidor for preserving the tobacco in a proper condition for use, and which provides a match box and striking strip for the matches.

With the foregoing and other objects in view, the invention will be more fully described hereinafter, and will be more particularly pointed out in the claims appended 30 hereto.

In the drawings, wherein like symbols refer to like or corresponding parts throughout the several views,

Fig. 1 is a plan view of an improved 35 smoker's kit constructed according to the present invention and in closed position;

Fig. 2 is a top edge view of the same;

Fig. 3 is a bottom edge view of the case;

Fig. 4 is a plan view of the case shown 40 open;

Fig. 5 is a longitudinal sectional view taken through the case on the line 5—5 in Fig. 5;

Fig. 6 is a transverse sectional view taken 45 on the line 6—6 in Fig. 5;

Fig. 7 is a similar view taken on the line 7—7 also in Fig. 5;

Fig. 8 is a cross sectional view taken on the line 8—8 in Fig. 5;

Fig. 9 is a vertical sectional view taken 50 on the line 9—9 in Fig. 5;

Fig. 10 is a perspective view of the match 55 holder; and

Fig. 11 is a similar view of the humidor unit.

Referring more particularly to the drawings, 1 designates generally a case made of a substantially rectangular form preferably slightly elongated and somewhat resembling a tobacco tin receptacle. The case may be 60 made of any suitable material, but it is preferably constructed of sheet metal. Partitions 2 and 3 divide a portion of the interior of the case from the remainder thereof and form a receptacle 4 for tobacco. The tobacco receptacle 4 opens through the bottom of the case and is accessible through a flanged cover 5 hinged as indicated at 6 to the lower end of the wall 3. The remainder of the bottom of the case is closed by a wall 70 7 which is rigid with the main body portion of the case. The flanges of the cover 5 are adapted to frictionally fit within the side walls of the receptacle 4 so as to remain closed through the effect of this tight fit 75 and are opened by force being applied to the bead 8 which extends slightly beyond the bottom.

Within the tobacco receptacle 4 and preferably placed against the vertical partition 3 is a humidor unit which, as more particularly disclosed in Fig. 11, consists of the two thicknesses 9 and 10 of a strip of metal bent upon itself intermediately as indicated at 80 11, and provided with numerous rows of intersecting perforations 12. Between the doubled thicknesses 9 and 10 is placed a blotter or other moisture absorbent pad 13 which is clamped tightly therebetween. If desirable, the lower thickness 10 may be left imperforate, and in order to effectively hold the pad 13 in position against the possibility of its accidental sliding laterally, the perforations 12 may be produced by punching the upper thickness 9 downwardly so 85 that the ragged edges of the punched perforations will embed themselves in the upper surface of the pad.

The free edge of the upper thickness 9 is curled upwardly and rolled over as represented at 14 in order to provide a finger piece useful in inserting and removing the humidor unit in and from the tobacco receptacle. The other free edge 15 is bent 90 upwardly against the upper thickness 9 beyond the adjacent edge of the pad. Metal 95

or other straps 16 are placed in the tobacco receptacle 4 and extend in close parallelism with the partition 3 so as to engage and removably and slidably hold in place the 5 humidor unit which is withdrawable downwardly when the cover 5 is opened fully. The partitions 2 and 3 intersect at a right angle and provide a space for a pipe alongside the same.

- 10 A block 17 is placed in the case with depressions 18 and 19 made to conform to substantially the stem and bowl of the pipe, and it is to be understood that the stem depression 18 may be curved to conform to 15 curved pipe stems, and the block and other adjacent parts of the case modified slightly where necessary to receive pipes of this character. A block 20, shown more particularly in Figs. 4 and 7, acts in conjunction 20 with the block 17 and is formed with depressions 21 and 22 being the counterparts respectively of the depressions 18 and 19. The block 20 is carried in a door 23 hinged as at 24 to one vertical side of the case and 25 is adapted to swing over upon the pipe and close the case. The free edge of the door 23 is provided with a depression 25 for occupancy by a boss 26 carried upon a flat spring 27 which urges the boss into the depression 25 and holds the door closed until 30 force is applied to open it. Of course, in practice, a little loose play will be allowed the spring to yield when the door is opened by force.
- 35 Cut off from the block 17 at the upper right hand end of the case by a partition 28 is a compartment 29 for receiving a match holder 30 which is provided with a closed top and a side wall slotted as indicated at 31 to permit insertion and removal 40 of the matches. This match holder 30 is slidable through the open top of the case and has a bead 32 projecting beyond the vertical walls of the case to admit of engagement by the fingers for the purpose 45 of prying the holder outwardly to give access to the matches. The slot 31 is such that the matches will topple over by the weight of the same and fall to a position 50 where their heads will project outwardly enabling them to be readily grasped and removed. At the same time the matches will engage the upper edge of the case when the match holder is moved inwardly causing 55 them to be pushed back into the holder. The match holder 30 next the partition 28 is provided with two notches or depressions 33 and 34 near its upper and lower ends respectively positioned for engagement by 60 a boss 35 carried by a spring arm 36 and projecting through a perforation 37 in said partition 28. The idea is to have the boss 35 engage the upper depression 33 when the match holder 30 is pressed home in the 65 compartment 29, thus serving to prevent

the accidental projection of the holder and the loss of matches.

When, however, the match holder 30 is drawn outwardly, it may be moved to a position where the lower depression 34 will be engaged by the boss 35, and this will tend to act as a check on completely withdrawing the match holder and it will also sustain the holder in an open position where subsequent matches may be withdrawn, and at the same time the striking strip 38 is exposed. The striking strip 38 is exposed through a slot 39 made in one wall of the match holder, and such strip is inserted through a slit 40 made in the adjacent wall of the holder. The engagement of the holder in the compartment 29 will prevent the striking strip 38 from being lost out of the slit 40.

In use, the holder 30 will be supplied with matches and a striking strip 38, the compartment 4 with loose tobacco, and a pipe will be carried between the blocks 17 and 20. The closed condition of the case is represented in Fig. 1 which is its normal position. When its use is desired the door 23 will be swung down by applying sufficient force to remove the depression 25 from the boss 26, the parts opening out to the position indicated in Fig. 4. The pipe may then be lifted from its position of repose in the depressions 18 and 19 of the block 17, after which the door 23 may be returned to its closed position. The case is then inverted and the cover 5 of the tobacco receptacle 4 opened and a quantity of tobacco poured into the bowl of the pipe. The cover 5 is then closed and the case righted.

Pressure is applied to the match holder to lift it to the position indicated in Fig. 4 whereupon the matches will swing out to the slot 31. A match is selected and scraped in the usual manner across the striking material 38 which also projects above the case.

The striking material 38 may be renewed from time to time by removing it through the slit 40 and substituting a fresh strip, and in a similar manner the pad or blotting material 13 in the humidor unit may be removed by prying apart the doubled over strip. The unit is also removed from time to time for the purpose of immersing it in water so that it may at all times impart the desired moisture to the tobacco.

It will be appreciated from the foregoing that I have provided an exceeding compact case which takes advantage of all of the space in a rectangular construction of this kind, and in which access may be conveniently had to the various articles necessary for smoking.

It is obvious that various changes and modifications may be made in the details of construction and design of the above specifi-

cally described embodiment of this invention without departing from the spirit thereof, such changes and modifications being restricted only by the scope of the following 5 claims.

What is claimed is:—

1. A smoker's kit comprising a case having a compartment for receiving tobacco opening through one end of the case and being of substantially the same thickness as the case, a compartment for a pipe opening through the side of the case and extending along one side and along a portion of the bottom of the tobacco receptacle, and a 10 match holder slidable in the case through the other end thereof and lying at one side of the pipe compartment and beneath the tobacco receptacle and being of substantially the same thickness as the case, substantially 15 as described.

2. A smoker's kit comprising a casing partitioned interiorly to provide a tobacco compartment, a space for a pipe extending at one side and partially beneath the tobacco 20 receptacle, and a compartment for matches at one side of the pipe compartment and beneath the tobacco receptacle, a cover for the tobacco receptacle opening through one edge of the case, a door for the pipe compartment 25 opening to one side of the case, and a slidable match holder movable into the match compartment through the opposite edge of the case, substantially as described.

3. A smoker's pipe kit comprising a sheet 30 metal case, partitions therein dividing the interior of the case to provide a tobacco receptacle in one end thereof with a space alongside for receiving the stem of a pipe and with a space beyond the bottom of the 35 receptacle for the bowl of the pipe, a reinforcing block in such spaces having depressions to receive such stem and bowl of the pipe, a door for opening and closing such spaces also provided with a reinforcing 40 block having depressions forming counterparts of the depressions previously referred to, a third partition in the case providing a 45 match compartment alongside the bowl

space, and a match holder slidable in such match compartments, substantially as described. 50

4. A smoker's kit comprising a case providing a tobacco receptacle and a compartment for a pipe, the receptacle opening through one edge of the case, and a slidable 55 match holder fitted in the case and opening through the opposite edge thereof, said match holder provided with a deep and wide slot therein closed at its top and adapted to allow the matches to swing outwardly from 60 beneath the top of the holder when such holder is projected beyond the case, substantially as described.

5. A smoker's kit comprising a case having a compartment for a pipe and a tobacco 65 receptacle therein, a slidable match holder in the case having a deep and wide slot in one side wall thereof and provided with a fixed and permanently closed top and depressions in another wall thereof near its 70 upper and lower ends, a spring pressed boss in the case adapted to enter said depressions to hold the holder in an open or closed position, and means for carrying a match striking strip alongside of the holder, substantially 75 as described.

6. A substantially flat rectangular case composed of a thin sheet metal body having an L-shaped space running along one side and partly along the top edge thereof and 80 being substantially half the thickness of the case, an L-shaped door hinged to the case at the side referred to and adapted to close flush with the case, reinforcing and pipe receiving blocks in the L-shaped space and 85 door, a tobacco compartment beside the pipe space and door and being of substantially the thickness of the case and projecting beyond the bowl receiving parts of the pipe space and door, said tobacco compartment 90 opening at the base edge of the case, a match compartment at the corner of the case where the tobacco compartment projects beyond the bowl space and door, and a slidable match holder therein.

SYDNEY BURT GARDNER.
